UNITED STATES PATENT OFFICE.

WILBURT B. DEAN, OF GRAND RAPIDS, MICHIGAN.

ELECTRIC-SPARK TIMER FOR GASOLENE-ENGINES.

1,272,334.

Specification of Letters Patent.

Patented July 9, 1918.

Application filed September 18, 1916. Serial No. 120,694.

To all whom it may concern:

Be it known that I, WILBURT B. DEAN, a citizen of the United States, residing at Grand Rapids, in the county of Kent and State of Michigan, have invented certain new and useful Improvements in Electric-Spark Timers for Gasolene-Engines, of which the following is a specification.

This invention relates to improvements in spark regulators or timers for use on gasolene engines, and its objects are: first, to provide a means whereby the electric igniting sparks for use on multiple engine cylinders may be exactly timed to meet the inflow of gasoline to cylinders at the exact desirable instant; second, to provide a spark timer that will be absolutely positive in its action at each and every contact, and, third, to provide a spark timer that may be readily adapted to special forms and makes of engines.

These objects are attained by the mechanism illustrated in the accompanying drawing, in which Figure 1 is a plan of the contact spring for this timer, showing how it may be applied to the actuating shaft; Fig. 2 is a longitudinal section of a short length of a spark chamber with this spark timer in place, and Fig. 3 is a cross section 30 of a spark chamber showing a plan of this timer in working position in the chamber.

Similar reference characters refer to similar parts in each of the several views shown in the accompanying drawing.

This invention is designed particularly for use on gasolene engines already on the market having very small spark chambers in which roller contact is used and the cylinder requires the use of some insulating substance between contact points, as, for instance, with the "Ford" engine in which the spark chamber is of very short diameter and uses a roller for contact. In this case the roller is wholly dispensed with and a spring actuated, sliding contact plate 1 is used. To bring this about it is necessary to provide a plate having considerable flexibility, and a long, reasonably strong spring, which would be impossible to attain with a spring extending outward from the central post or shaft of the timer.

This invention, therefore, consists practically in the construction of the spring that carries and governs the contact points on the traveling contact plate. To provide the necessary spring for this purpose a round

metal body, 1, is formed with a slot 3 cut out in it forming an inner rim 2 having a spring connection with the part 1, as at 4, so that the part 1 will be suitably supported upon the revoluble central shaft 11. The means used to properly secure this plate onto the shaft 11 is to place the plate upon the collar 14, place a collar 13 upon this plate, place the second plate upon this collar, then place the collar 12 upon the second plate and secure them all firmly in place by any available means, as with a nut 16 screwed upon the end of the shaft 11.

The spring plates 1, 1 are provided with contact points 5, 5 that are designed to pass both sides of the plates 7 in the cylinder 6. In this instance a timer is shown that is designed for a nest of four engine cylinders hence four pairs of plates, 7, are shown in the cylinder 6, in Fig. 3, and to increase the number of spark contacts it is only necessary to increase the number of the contact plates 7 to correspond with the number of cylinders to be operated. The contact points 5 are bent to curve from each other, at the ends, so that they will be absolutely positive to pass astride the contact plates or points 7, 7 whenever approaching them, and they are made sufficiently rigid by the long spring, formed by the body 1 extending around the center shaft and connected at 4, so that the contact with the plates 7, 7 will be strong and effective. It will be distinctly understood that while the part 2 is firmly clamped between the flanges 12, 13 and 14, the dividing groove 3 carries the inner edge of the part 1 absolutely free from these flanges on the side adjacent to the contact points 5 so that the positions of these points may be varied to a considerable degree without in any way straining any of the contact plates, and at the same time the contact between the points 5 and 7 will be perfect, complete and positive in results.

With this construction, as an air space exists between the points 7, 7 and as the points 5, 5 do not come in contact with any metal except when contacting with the points 7, 7 it is not necessary to use any form of insulating substance between the points 7, 7, though the points 7—7 must be insulated from the cylinder 6, as indicated at 17.

While it is a fact that spark timers have been made and used where contact points similar to the points 5, 5 and 7, 7 are op-

erated without the use of any insulation between the points 7, 7 except the air spaces, it is, also, a fact that in all such constructions there has been sufficient space in the cylinders to allow of placing the necessary length of spring to properly actuate the plates or points represented at 5, 5 between their supporting flanges and the plates represented at 7, 7 to provide all of the variation in the relative positions of the points 5 and 7 necessary to meet all conditions, but in this instance the appliance is for use in small cylinders, hence the special spring shown, that is, extending to the farther side of the supporting shaft, from the contact points, so a considerable variation in the positions of the points 5, 5 may be attained with little or no dangerous strain upon the springs, and in this construction lies the principal features of the invention.

If deemed advisable a collar 9 may be firmly secured on the shaft 11 and provided with a notch 15 to receive the lug 10 and positively avert the danger of the plate 2 being carried around when the points 5, 5 are contacting with the points 7, 7.

The coils 8, are placed simply to indicate the electric connection necessary to properly create the spark, when contact is made between the contact points 5, 5 and 7, 7, as hereinbefore suggested, without regard to necessary positions in actual construction.

The new features in this invention, and those upon which patent protection is desired are:

1. In combination with a cylinder having contact points extending inward from the inner surface thereof, and the central revoluble shaft of an electric spark timer for gasoline engines; a substantially annular spring metal plate having a contact point extending from one position of its edge in position to successively engage the contact points in the cylinder, said metal plate having a groove cut around outside of its connection with the shaft in such manner as to leave a connecting neck between the outer

and inner circles thus formed, upon the side of the shaft bearing opposite from the contact point thus forming a spring member 50 extending from the contact point around the shaft bearing and to the opposite side thereof, to insure perfect contact between the contact points on the plates and the contact points in the cylinder.

2. In combination with a metal cylinder having contact points equally spaced and extending inwardly from the inner periphery of the cylinder, and a revoluble shaft concentric of the cylinder, in spark timers for gasoline engines; annular plates securely mounted on the shaft and having a slot formed therein and extending nearly around outside of the shaft bearing forming a connecting neck at one point, contact points 60 formed at the edge of the outer circle of said plate opposite to the connecting neck and in position to successively engage the several points in the cylinder as the shaft revolves, said outer circles of said plates 65 forming long flexible springs to insure perfect contact between the contact points on the plates and the contact points in the cylinder as the shaft revolves.

3. In combination with a metal cylinder 75 having inwardly extending contact points, and a centrally located revoluble shaft mounted therein; annular plates securely mounted on the shaft and having circular slots formed through just outside of the 80 shaft bearings and arranged to form a narrow spring neck connecting the inner circle and the outer circle of each of said plates, a contact point formed on each plate opposite from the connecting neck, the ends of 85 said contact points bent outward from each other to insure perfect contact between the points on the plates and the points in the cylinder, the outer circles of the plates forming long flexible springs for use in short 90 space.

Signed at Grand Rapids, Michigan, September, 1916.

WILBURT B. DEAN.
